METHOD AND APPARATUS FOR SHUTTING OFF WATER INTRUSION THROUGH PERFORATED CASINGS

Olney P. Yowell, Whittier, Calif., assignor to O. P. Yowell Service Company, a corporation of California

Application April 20, 1936, Serial No. 75,351

13 Claims. (Cl. 166—21)

This invention has to do in a general way with oil well operations and is primarily concerned with an improved method and apparatus for shutting off water intrusion through the perforated casing in an oil well.

As is well known to those familiar with the art, it frequently happens in oil well practice that the perforated casing which is situated in the oil zone or oil sand and through which the oil is received for removal from the well, may be located in a zone which in addition to the oil sand contains a stratum of water sand from which water enters the perforated casing to contaminate the oil.

Various types of electrical, chemical and photoelectric apparatus have been devised for locating the regions of water intrusion and after locating such region of water intrusion it is the usual practice to attempt to fill the perforations in the region of the formation surrounding this zone of intrusion with cement. It frequently happens that after this is done it is found that the contamination of the oil with the water continues and the reason for this, I have discovered, is that the small strainer perforations in the casing in the region where they are exposed to water soon become corroded, forcing the water to migrate from the water stratum up into the oil stratum so that it actually enters the perforated casing at a point spaced remotely from the actual water zone. It therefore becomes a primary object of this invention to devise a method of the class described which may incorporate as an initial step a procedure whereby the actual water stratum which is the source of the contamination, may be accurately located.

In view of the fact that the perforations or strainer openings in the perforated casing are comparatively small, and further in view of the necessity of obtaining the maximum penetration of cement into the formation in order to obtain a positive shut-off of water, my invention contemplates as an additional step under circumstances where the perforations are small, the formation of new large perforations in the wall of the casing before the placement of cement therein.

In order to obtain the maximum penetration of cement into the formation, my invention contemplates as a further step the discharge of such cement in the region or zone to be cemented under a substantial pressure and to safeguard against the migration of appreciable amounts of cement slurry beyond the objective zone of cementation due to pressure differences inherent in

the formation or due to the pressure under which the cement is actually applied, my invention contemplates the initial placement of cement bridges at the two extremities of the water zone, such bridges extending out into the formation so as to provide a positive seal between the outer surface of the perforated casing and the surrounding formation at the two extremities of the water zone.

The bridge referred to above becomes particularly important in connection with the upper end of the zone to be cemented since it is important that the return of cement into the perforated casing around the cement discharging apparatus be prevented.

Further, to prevent the possibility of cement slurry returning to the perforated casing in the region of the water zone above the point of delivery and thereafter rising in the perforated casing into the region above the water zone, it becomes a further object of this invention to provide a cement discharging apparatus which is equipped with sealing or packing means surrounding the cement discharge conduit and positioned so as to always maintain a seal between the cement discharge conduit and the interior of the perforated casing in the region of the upper bridge.

My invention also contemplates a novel form of cement discharging apparatus equipped with packing means for the purpose referred to above and also equipped with a valve whereby the fluid in the casing may be by-passed up through the cement delivery tubing during the installation of the tool in the well. This valve is equipped with means for positively closing the same after the pressure discharge of cement has been made whereby the pressure may be held on the cement so applied and back circulation may be set up through that portion of the casing above the tool in order to insure the removal of any cement slurry which may have leaked past the tool into the region thereabove. In this connection my invention contemplates a tool which is equipped with an inwardly opening check valve in the cement delivery pipe through which such back circulation may be maintained.

The details in the procedure contemplated by this invention as well as certain details in the construction of a preferred form of apparatus for use in connection therewith will be best understood from the following description of the accompanying drawings which are chosen for illustrative purposes only and in which,

Fig. 1 is a sectional elevation of more or less diagrammatic character, illustrating a perfo-

rated casing in an oil well and further showing the manner in which corrosion is set up in the perforations of that portion of the casing which occupies the water zone or stratum;

5 Fig. 2 is a sectional elevation similar to Fig. 1 illustrating the step of cleaning the corroded perforations;

Fig. 3 is a sectional elevation illustrating the step of forming enlarged perforations in the casing for the discharge of cement from the casing into the formation;

10 Fig. 4 is a sectional elevation illustrating a casing which has been cleaned and perforated and further illustrating the results of the initial 15 operation followed in a preferred procedure of placing bridges at the two extremities of the water zone;

15 Fig. 5 is a sectional elevation which shows the cement plug contained within the casing at the 20 region of the upper bridge as having been removed which is the condition present in the casing just prior to the final cementing operation;

20 Fig. 6 is a sectional elevation illustrating the final cementing operation and a preferred form 25 of apparatus which may be employed in effecting this operation;

25 Fig. 7 is a sectional elevation illustrating the final result of my process, the cement contained within the casing having been drilled therefrom 30 to leave an impervious wall in the region of the casing which occupies the water sand or zone; and

30 Fig. 8 is a sectional elevation illustrating a modified form of cement discharging apparatus.

35 More particularly describing the invention as herein illustrated and referring first to Fig. 1 which, as pointed out above, illustrates a portion of a perforated oil well casing contained in a water sand or water zone, reference numeral 40 11 indicates a bore hole or well which contains a casing 12 provided with the ordinary slots or "screen" perforations indicated at 13. Reference numeral 14 indicates a water sand or water zone which is shown as being between two oil 45 sands indicated at 15 and 15'.

It will be observed that the perforations in the casing which are situated in the region of the water zone have accumulated corrosive matter so that they are plugged as indicated by reference 50 numeral 16. These perforations being plugged, cause the water in the zone 14 to migrate in opposite directions along the walls of the bore hole as indicated at 17 and 17' so that the water 55 may enter the perforated casing at a substantial distance from the zone or region in which it has its source. It will thus be seen that if an attempt is made to locate the position of the water sand with any of the conventional water 60 locating means which are lowered within the casing, with a casing such as is shown in Fig. 1, that the region or regions so located may be spaced a substantial distance from the actual source of the trouble and any effort to cement off or stop the water intrusion based on a location 65 of this character will be unsatisfactory.

I therefore consider it important as a first step in the process contemplated by this invention to wash all of the perforations in the casing clear of any encrustation or corrosive matter which 70 may have accumulated therein so that the fluid entering the perforations throughout the entire length of the perforated casing will be indicative of the formations surrounding the casing at the point of fluid entry.

75 Various types of apparatus may be employed

for effecting this washing operation. In other words, any of the conventional pressure or suction perforation washers may be used. For the purpose of illustrating this step in the process of my invention I have shown in Fig. 2 a washing 5 apparatus which simultaneously combines pressure and suction in two adjacent zones of the formation. Since the details in the construction and operation of this washer form no part of the present invention, I will make no attempt 10 to describe its structural details. However, for purposes of clarity the washer may be described as consisting in a general way of a hollow mandrel or tubing 20 suspended through the medium of a tubing 21 from the surface of the ground. 15 The lower end of the tubing 20 is shown as being provided with a guide shoe 22 and such tubing is provided at extreme end portions with packing members 23 and 24 which are rigidly mounted thereon. The intermediate portion of 20 the tubing slidably extends through a sleeve section 25 which is equipped with a slip assembly 26 associated with an anchor member 27 adapted to guide the slips thereon, the sleeve 25 also carrying a packer or a plurality of packers indicated generally by reference numeral 27'. When this assembly is lowered into the desired position within the perforated casing the slip assembly 20 is released through the medium of a bayonet lock 28 so that the further application of weight 30 causes the slips to expand into engagement with the inner surface of the casing thereby locking the sleeve 25 and its associated packer against further movement. Continued downward movement of the tubing 20 with its packers 23 and 35 24 causes the space between the packer 27' and the packers 24 to contract and at the same time causes the space between the packer 27 and the packer 23 to expand. In this way pressure is applied within the casing between the packers 40 24 and 27 and suction is applied within the casing between the packers 27 and 23. The differential pressure between the interior and the exterior of the casing during the application of such pressure and suction is effective to clean 45 or open the perforations in the particular zone where the tool is located.

In actual operation this cleaning procedure is carried out through the entire length of the 50 perforated casing and after such cleaning operation has been completed the water locating apparatus of any conventional type such as a chemical, electrical or photoelectric "Water Witch" is lowered into the perforated casing and the zone or zones of water intrusion are located. 55

Assuming conditions such as are illustrated in Figs. 1 and 2, this water locating apparatus will establish the limits of the water zone as being between the points A and B of Fig. 2.

As is well known to those familiar with the 60 art, most of the conventional perforated or strainer casings are provided with perforations in the form of small slots or openings equipped with buttons, such buttons being provided with small slots and in the event this is the type of 65 casing with which the process is being carried out, it is desirable in order to secure the most positive results, to provide the region of the casing wall in which the water intrusion is to be closed off with enlarged perforations through 70 which a cement slurry can be readily forced into the formation from the interior of the casing.

For the purpose of providing these enlarged 75 perforations any conventional casing perforator may be employed. Fig. 3 illustrates the perfo-

rating step and in connection therewith shows a perforator which consists of a body 30 supported in the casing through the medium of a tubing 31 or other suitable suspending means, such body 5 having an elongated groove 32 therein which carries the pivoted cutter or blade 33 at its upper end. The blade is adapted to be swung outwardly into perforating engagement with the casing through the medium of a tongue member 10 34 which is slidably and pivotally mounted in the lower end portion of the groove, such tongue member being actuated during downward movement of the body by means of a releasable anchor member generally indicated by reference 15 numeral 35. This anchor member carries a tail piece 36 slidably mounted on a mandrel 37 and adapted to be latched against movement with respect thereto. The upper end of the mandrel 20 37 carries a wedge block or shoe 38 positioned behind the tongue 34 and adapted to wedge the same against the wall of the casing when the tail piece is latched to the mandrel and the body is moved downwardly relative to the tail piece. The tongue is provided with a casing gripping 25 member in the form of a serrated wheel indicated at 39. As was pointed out above the particular perforating tool forms no part of the present invention and for a more complete description of its construction and operation, reference is made to the co-pending application of Robert S. Smith, Serial No. 76,567, filed April 27, 1936, now matured into Patent No. 2,046,752, dated July 7, 1936, which is assigned to the assignee of the present application.

35 In the perforating step, which, as will be understood by those familiar with the art may be eliminated in the event the perforated pipe or casing is of a character such that cement slurry will readily flow through the openings 40 therein, it is preferable that the perforations be started at a point slightly below the lower extremity B of the zone of water intrusion and that they be carried to a point slightly above the upper extremity A of such zone, these enlarged 45 perforations being indicated generally by reference numeral 40 in Fig. 3.

As was pointed out above, it is a principal object of this invention to provide a process in which the water sand or zone of water intrusion 50 can be positively isolated from the oil sand in the region outside of the perforated casing prior to the closing off of the perforations within the casing in the actual water zone. In other words, my invention contemplates as one of its primary 55 objects the placement or provision of what I may term bridges which surround the perforated casing and are sealed or locked in the formation at the two extremities of the water zone. The placement of these bridges is accomplished 60 preferably by first installing a plug member 50 within the casing at a point below the lower extremity of the water zone and then supplying cement in any conventional way into the casing above this plug, such cement being supplied in 65 a manner such that it is discharged through the perforations of the casing and is forced out into the formation forming a cement plug 51 within the casing and a cement bridge 52 which surrounds the casing in the oil shale adjacent the 70 water sand. After this plug has been installed, a second plug 53 is placed within the casing at the upper extremity of the water sand which is followed by the installation of a cement plug 54 and an encasing cement bridge 55 which surrounds the perforated casing in the oil shale. 75

After the cement plugs and bridges 54 and 55 have had an opportunity to set, the cement plug 54 and its supporting plug 53 are drilled from the interior of the casing by means of any suitable drilling apparatus which leaves the casing open down to the plug 51 and leaves the portion of the perforated casing at the upper extremity of the water zone encased in a cement bridge 55 preferably of substantial length, which positively seals that portion of the bore hole which 10 extends through the oil shale above the bridge from the water sand. The oil shale below the water sand is correspondingly sealed by the bridge 52. The result of this operation is illustrated in Fig. 5, and the next step in the operation entails the placement of cement within that portion of the casing which occupies the water sand under sufficient pressure to completely encase the casing with cement thereby preventing water intrusion. The bridge 55 serves a purpose 15 additional to that pointed out above in that it may be used to prevent the migration of cement slurry back into the perforated casing at a point above the water zone where it might cause the cementing apparatus to be frozen in the casing 20 or where it might serve to plug the perforations in the region of the oil zone which must be kept clear in order to obtain the maximum oil production.

In Fig. 6 I show a preferred form of apparatus 30 which may be employed for performing the final cementing operation, such apparatus being designed to maintain at a minimum the migration of cement back into the casing from the water zone. This apparatus consists of a cement discharge conduit 60 having discharge openings 61 at its lower end, such conduit being provided with a plurality of spaced packers 62 starting from a point immediately above the discharge end 61 and extending at predetermined spaced 40 intervals throughout the full length of the discharge conduit 60. The discharge conduit 60 is formed of a length slightly greater than the distance between the two bridges 55 and 52 and the distance between the successive packers 62 45 is slightly less than the length of the bridge 55 as observed by the operator when it was installed.

The upper end of the discharge conduit 60 is connected with a fitting 64 which in turn is connected to a cement delivery pipe 65. The fitting 64 is provided with a valve seat 66 which is associated with a valve 67 mounted on the lower end of a valve stem 68 which is slidably supported in a spider 69 and is biased toward a closed position by means of a compression spring 70. The upper end of this valve stem is adapted to be engaged by a valve opening stem 71 which is mounted on a spider 72 in the bottom of the tubing 65. With this arrangement it will be 60 seen that the valve may be opened and closed by rotating the tubing 65 in its threads 73 whereby it is attached to the box in the upper end of the fitting 64. Reference numeral 75 indicates an inwardly opening check valve which is positioned in the bottom portion of the tubing 65, the purpose of which will appear from the description of the operation of this cementing tool.

After the top cement plug 54 has been drilled from the casing to obtain the result illustrated in 70 Fig. 5, the cementing tool shown in Fig. 6 is assembled with the threaded connection 73 arranged so as to hold the valve 67 open. This assembly is then lowered into the casing, the valve 66 permitting the by-pass of the fluid in the well up- 75

wardly through a tubing 65. The cement discharging assembly is lowered down within the casing to the position shown in Fig. 6 at which its discharge end rests on the bottom bridge 51. A 5 cement slurry of suitable consistency and under a substantial pressure is then delivered into the discharge pipe 60 through the delivery conduit 65 and as this cement under pressure is delivered into the casing, the conduit 65 and its associated 10 discharge conduit 60 are gradually raised. As pointed out above, the packing members 62 are spaced on the pipe 60 at distances slightly less than the length of the bridge 55 so that one of these packing members is always contained in 15 the region of the casing surrounded by the bridge 55, thereby maintaining a positive pressure seal between the zone surrounding the region of the casing in which the cement is being applied and the region of the perforated casing above the 20 bridge 55. Since the bridge 55 prevents the migration of cement slurry upwardly along the bore hole into the oil shale it will be seen that the packing members 62 sealing the interior of the casing in the manner just described, co-operate with the 25 bridge to prevent the migration of cement into the region above the bridge 55 through the interior of the casing.

This cement discharging operation is carried on until the delivery conduit has been raised a 30 distance corresponding to the distance between the two bridges. When this has been accomplished the conduit 55 is rotated to unscrew the threads 73 a sufficient amount to permit the closure of the valve 67 whereby the cement plug 35 so installed is held under pressure.

In order to insure the removal of any cement slurry which may possibly have leaked into the perforated casing above the uppermost packer, I consider it preferable to next circulate a washing 40 fluid, such as mud or the like, downwardly through the casing from the surface of the ground, such fluid being returned with any cement slurry which may have accumulated therein through the bypass valve 65. After this has been done and the 45 desired time has elapsed, the cementing tool is then withdrawn from the well, leaving the region of the perforated casing which occupies the water sand completely filled with a cement plug and completely surrounded with a wall or encasement 50 of cement which has been forced out into the formation under a substantial pressure.

The next operation in the event the water zone is situated between two portions of oil producing shale or sand, is to drill the cement from the 55 interior of the casing thereby leaving an open pipe provided with perforations in the oil zone to be encased with a water impervious wall of cement 78 in the region of the water zone.

Fig. 8 shows a modified form of cementing apparatus which is preferably designed for use 60 where the water intrusion is taking place at the bottom of the hole, since this apparatus is one in which no particular precautions are taken to prevent the return of cement slurry into the casing 65 around the cement discharge conduit. This apparatus is shown as comprising a cement discharge conduit 80 having a guide shoe 81 at its lower end and provided with a packing member 82 situated above the guide shoe and above the 70 cement discharge openings 83. A conduit 80 is shown as being provided with another guide collar 84, top packing members 85 and a connection 86 whereby it is attached to the cement delivery conduit 87. This form of cement discharging apparatus may, as was pointed out above, become 75

frozen in the casing at the end of the cementing operation. In the event the zone or region of water intrusion is at the bottom of the hole, it will be the practice to merely unscrew the conduit 87 from the fitting 86 and leave the remainder of the 5 tool in the well. In the event this type of apparatus is used for shutting off intermediate water intrusion, it will in the event it becomes "frozen" in the hole, be necessary to remove it from the casing by a milling operation. Bearing this point 10 in mind, it will be seen that other types of apparatus may be employed for delivering the cement into the casing but to facilitate the removal of the tool and the delivery of cement into the desired zone under a substantial pressure, I consider it 15 preferable to use an apparatus of the type shown and described in connection with Fig. 6 which embodies features of novelty that are claimed as a part of this invention.

It will be understood that while I have herein 20 described and illustrated one preferred procedure contemplated by this invention, that various steps of the procedure may be eliminated depending upon the type of casing used and the well conditions encountered, also that while I have herein 25 described and illustrated certain preferred forms of apparatus to be used in the practice of this process, that other types of apparatus may be used without departing from the scope of the invention as expressed in the appended claims. 30

I claim as my invention:

1. A method for shutting off intrusion from a water zone through the perforated casing of an oil well which includes: placing a cement plug and bridge in and around said casing at the lower extremity of said water zone; surrounding said casing with a cement bridge at the upper extremity of said water zone; discharging cement under pressure within said perforated casing near said bottom plug and bridge; and gradually raising the point of discharge of said cement at the same time maintaining a seal within said casing in the region of said upper bridge. 35

2. A method for shutting off intrusion from a water zone through the perforated casing of an oil well which includes: placing a cement plug and bridge in and around said casing at the lower extremity of said water zone; surrounding said casing with a cement bridge at the upper extremity of said water zone; discharging cement under pressure within said perforated casing near said bottom plug and bridge; gradually raising the point of discharge of said cement at the same time maintaining a seal within said casing in the region of said upper bridge thereby filling and 50 surrounding the casing with cement in the region of said water zone; and drilling the cement from the interior of said casing after it has set. 55

3. A method of shutting off intrusion from a water zone through the perforated casing of an oil well which includes: locating the upper and lower limits of said water zone; forming a plurality of open perforations in said casing in the region of said water zone; forming cement bridges in the formation surrounding said casing at the two extremities of said water zone; and forcing cement under pressure into said casing and the formation surrounding same between said bridges. 60

4. A method of shutting off intrusion from a water zone through the perforated casing of an oil well which includes: locating the upper and lower limits of said water zone; forming a plurality of open perforations in said casing in the region of said water zone; forming cement bridges in the formation surrounding said casing; forc- 70 75

ing cement under pressure into said casing and the formation surrounding same between said bridges and drilling the cement from the interior of said casing after it has set.

- 5 5. A method of shutting off intrusion from a
water zone through the perforated casing of an
oil well which includes: locating the upper and
lower limits of said water zone; forming a plu-
rality of open perforations in said casing in the
10 region of said water zone; forming cement bridges
in the formation surrounding said casing at the
two extremities of said water zone; forcing cement
under pressure into said casing and the forma-
tion surrounding same between said bridges;
15 maintaining a seal within said casing in the re-
gion of said upper bridge during said last men-
tioned cementing operation; and drilling the ce-
ment from the interior of said casing after it
has set.

20 6. A method of shutting off water intrusion
through the perforated casing of an oil well which
includes the steps of: cleaning the perforations
in said casing; locating the upper and lower ex-
tremities of the region of water intrusion through
25 said perforations, forming cement bridges in the
formation surrounding said casing at the two ex-
tremities of said region of water intrusion; and
forcing cement under pressure into said casing
and the formation surrounding same between said
30 bridges.

7. A method of shutting off water intrusion through the perforated casing of an oil well which includes the steps of: cleaning the perforations in said casing; locating the upper and lower extremities of the region of water intrusion through said perforations, forming cement bridges in the formation surrounding said casing at the two extremities of said region of water intrusion; forcing cement under pressure into said casing and the formation surrounding same between said bridges; maintaining a seal in said casing in the region of the upper bridge during said last mentioned cementing operation; and drilling the cement from the interior of said casing after it has set.

35

36

40

45

- 40 set.

8. A method of shutting off water intrusion through the perforated casing of an oil well which includes the steps of: cleaning the perforations in said casing; locating the upper and

50 lower extremities of the region of water intrusion through said perforations; forming a plurality of large perforations in the wall of said casing in said region of water intrusion; forming cement bridges in the formation surrounding

55 said casing at the two extremities of said region of water intrusion; forcing cement under pressure into the casing and the formation surrounding same between said bridges; maintaining a seal within said casing in the region of the

60 upper bridge during said last mentioned cementing operation; and drilling the cement from the interior of said casing after it has set.

9. A method of shutting off water intrusion through the perforated casing of an oil well which includes the steps of: cleaning the perforations in said casing; locating the upper and lower extremities of the region of water intrusion through said perforations, forming cement bridges in the formation surrounding said casing at the two extremities of said region of water intrusion; forcing cement under pressure into

said casing and the formation between said bridges; thereby filling such region of the casing and the surrounding formation with cement; maintaining a packing seal in said casing above the point of cement discharge during said last mentioned cementing operation; and then back circulating a washing fluid down through said casing and up through an internal conduit after said cement has been installed.

10. A method of shutting off intrusion from
a water zone through the perforated casing of
an oil well which includes: locating the upper
and lower limits of said water zone; forming a
plurality of open perforations in said casing in
the region of said water zone; forming cement
bridges in the formation surrounding said casing
at the two extremities of said water zone;
forcing cement under pressure into said casing
and the formation surrounding same between
said bridges through a cement delivery tubing
extending from the surface of the ground; and
maintaining a packing seal between said delivery
tubing and said casing in the region of said up-
per bridge during said last mentioned cementing
operation. 20 25

11. A method of shutting off intrusion from a water zone through the perforated casing of an oil well which includes; locating the upper and lower limits of said water zone; forming a plurality of open perforations in said casing in the region of said water zone; forming cement bridges in the formation surrounding said casing at the two extremities of said water zone; forcing cement under pressure into said casing and the formation surrounding same between said bridges through a cement delivery tubing extending from the surface of the ground; maintaining a packing seal between said delivery tubing and said casing in the region of said upper bridge during said last mentioned cementing operation and circulating a washing fluid down through said casing and up through said delivery tubing in the region above said seal after said last mentioned cementing operation. 30 35 40

12. For use in supplying cement under pressure to the interior of a perforated casing for the purposes described: an elongated tubing having a cement outlet at its lower end; a plurality of packing members mounted on said tube above said outlet in predetermined spaced relation with each other; conduit means for delivering cement into the upper end of said tube; a valve in the upper end of said tube; and means operable by relative rotation between said delivery conduit and said tube for actuating said valve. 55

13. For use in supplying cement under pressure to the interior of a perforated casing for the purposes described: an elongated tubing having a cement outlet at its lower end; a plurality of packing members mounted on said tube above said outlet in predetermined spaced relation with each other; conduit means for delivering cement into the upper end of said tube; a valve in the upper end of said tube; means operable by relative rotation between said delivery conduit and said tube for actuating said valve; and an inwardly opening check valve mounted in the wall of said tube above said last mentioned valve. 60 65
